UNITED STATES PATENT OFFICE.

JOHN ALLEN HEANY, OF YORK, PENNSYLVANIA, ASSIGNOR TO THE TETER-HEANY DEVELOPING COMPANY, OF CHARLESTON, WEST VIRGINIA, AND YORK, PENNSYLVANIA, A CORPORATION OF WEST VIRGINIA.

MACHINE FOR APPLYING COVERINGS TO WIRE.

No. 825,123.

Specification of Letters Patent.

Patented July 3, 1906.

Application filed January 20, 1904. Renewed December 22, 1905. Serial No. 292,968.

To all whom it may concern:

Be it known that I, JOHN ALLEN HEANY, a citizen of the United States, residing at York, in the county of York and State of Pennsylvania, have invented certain new and useful Improvements in Machines for Applying Coverings to Wire, of which the following is a specification.

My invention has relation to a machine adapted to apply to a wire a covering of preferably insulating material, and in such connection it relates more particularly to mechanism of such a machine whereby the wire may be unwound from a reel, properly fed through the machine while the wire is rotating, and then wound upon a second reel after the covering is applied.

In United States Letters Patent No. 740,131, granted to me under date of September 29, 1903, there is described and claimed a method of producing insulated electric conductors, and among the steps set forth as part of the method are those which prescribe that the wire must travel and must rotate while traveling through certain baths and during the application of asbestos fiber to the wire and the compacting of the fiber upon the wire. In the present application a preferred form of machine is illustrated designed to carry out the steps of feeding the wire and rotating the same during the feeding operation.

The nature and scope of my present invention will be more fully understood from the following description, taken in connection with the accompanying drawings, forming part hereof, in which—

Figure 1 is a side elevational view of a machine embodying main features of my invention, certain parts of the machine being broken away. Fig. 2 is a top or plan view thereof. Fig. 3 is an enlarged detail view of the mechanism for unwinding, feeding, and rotating the wire, certain parts being illustrated in section. Fig. 4 is an enlarged end elevational view of the friction-sleeve upon the arbor supporting the reel. Fig. 5 is a view similar to Fig. 3, but illustrating the mechanism for winding up the covered wire. Fig. 6 is an enlarged cross-sectional view on the line 6-6 of Fig. 3. Fig. 7 is a view similar to Fig. 6, the section being taken on the line 7-7 of Fig. 3. Fig. 8 is a detail side elevational

view, still further enlarged, of the mechanism for laying the covered wire upon the reel. Fig. 9 is an end elevational view of Fig. 8, and Figs. 10, 11, 12, and 13 are enlarged detail views illustrating the construction of the reel upon which the covered wire is wound.

Referring to the drawings, *a* represents the framework of the machine, supporting at one end the unwinding mechanism *A* and at the other end the winding mechanism *B*. The frame *a* also supports intermediate of its ends certain mechanisms *D*, *E*, *F*, *G*, and *H* for respectively covering the wire with glue, asbestos, and a fireproof coating and for compacting and drying the covering on the wire prior to winding it up in the winding mechanism *B*. These mechanisms *D*, *E*, *F*, *G*, and *H* form the subject-matter of companion applications for patents, and a detailed description of the same is not necessary for a proper understanding of the present invention.

Referring now to Figs. 3 and 4, the unwinding mechanism *A* consists, essentially, as follows: In bearings *a'*, projecting upward from the frame *a*, is mounted an arbor *a²*, surrounded by a sleeve *a³*, to which is keyed or otherwise secured a driving-pulley *a⁴*, connected by a belt with the driving-shaft *a⁵* of the machine. Upon the inner end of the arbor *a²* is detachably secured the reel or spool *e*, upon which the uncovered wire *e'* is wound. The preferred means of detachably securing the reel *e* to the arbor *a²* is as follows: Upon the arbor *a²* is secured a conical piece *e²*, and on the screw-threaded end of the arbor is adapted to be advanced a conical thumb-nut *e³*. The reel *e* is clamped between the nut *e³* and piece *e²*, when the nut is advanced upon the spindle, and by removing the nut *e³* the reel *e* may be readily slipped off of the arbor *a²*. The arbor *a²* is normally held from turning by the following preferred means: Upon the outer end of the arbor *a²* is secured a friction-disk *e⁴*, having a grooved periphery surrounded by a split band *e⁵*. The band at its lower end is bolted or otherwise secured to the bearing *a'*, and the two ends of the band *e⁵* are connected by an adjustable bolt *e⁶*, by turning which the band *e⁵* may more or less tightly engage the disk *e⁴*. The reel *e* being clamped to the arbor *a²* and the arbor *a²* being normally held from rotating, it fol-

lows that the reel e remains stationary under ordinary circumstances during the unwinding operation. Secured to the sleeve a^3 , which rotates with the driving-pulley a^4 , is a frame f , having on one of its arms a roller f' , over which the wire e' passes as it leaves the reel e . This frame f and roller f' rotate or revolve around the reel e to unwind the wire therefrom. If the speed of revolution of the frame f is too great to permit of the proper take-off of wire from the reel e , the pull upon the reel e becomes great enough to overcome the friction of the band e^5 upon the disk e^4 , and hence the reel e , arbor a^2 , and disk e^4 are permitted to turn sufficiently to relieve the tension on the wire e' . The frame f terminates at its free end in two arms f^2 and f^3 , preferably arranged as illustrated in Fig. 3 and in detail in Figs. 6 and 7. Referring to these figures, it will be found that the arms f^2 and f^3 are oppositely arranged to form a box surrounding a tubular piece g , through which the wire is to pass, and the box-shaped ends of the arms f^2 and f^3 are inclosed by a tubular stationary bearing g' , fixed to a standard a^{10} of the machine in a suitable manner. Each arm f^2 f^3 is provided with a gear-wheel g^2 g^3 , respectively, the teeth on the periphery of which wheels are slightly inclined. The gear-wheels g^2 g^3 each carry a grooved roller g^4 g^5 , between the contiguous peripheries of which the wire e' is fed when the gear-wheels g^2 g^3 are turned. The grooves of the rollers g^4 g^5 are arranged at diametrically opposite sides of the axis of rotation of the frame and not only revolve around said axis, but also rotate in a plane passing through said axis. To turn the gear-wheels g^2 and g^3 , the rotary motion of the arms f^2 and f^3 is utilized by causing the teeth of the gear-wheels to engage a cam-rib g^6 , projecting from the face of the stationary tubular bearing g' . As the frame f revolves the rollers g^4 and g^5 are positively driven to rotate the wire and to feed the same through the machine as it is unwound from the reel e by the frame f . From such a construction and arrangement of parts it is manifest that the feeding of the wire e' is dependent upon the speed at which it is unwound from the reel e , and hence that buckling of the wire e' is prevented.

The mechanism B for winding up the wire after it has been covered and coated during its passage through the machine is substantially the same as that of the unwinding mechanism A, as a comparison of Fig. 5 with Fig. 3 will readily show. There are some additional elements necessary, however, in the winding mechanism, due to the fact that the wire by reason of its coating and covering has increased in diameter, and some provision must be made for winding the covered wire smoothly upon its reel e^{10} . Again, some provision must also be made to permit the wire when wound upon the reel e^{10} to be

readily removed therefrom, and some changes in the structure and arrangement of the reel and its operating and supporting parts are consequently necessary. In the winding mechanism B a sleeve b^3 , driven by a pulley b^4 , rotates in bearings b' , supported by the framework of the machine. A frame f^{10} , secured to the sleeve b^3 , revolves therewith around the reel e^{10} . The arms of the frame f^{10} carry gear-wheels g^2 and g^3 , each provided with grooved rollers g^4 and g^5 , and the teeth of the gear-wheels g^2 and g^3 engage, as hereinbefore described, a cam-rib g^6 , projecting from the face of the stationary tubular bearing g' . The frame f^{10} in revolving positively drives the feed-rollers g^4 and g^5 , to thus rotate and draw the covered wire e^{11} toward the reel e^{10} . On the frame f^{10} is a roller f^{11} , over which the wire e^{11} travels on its way to the reel e^{10} . This roller f^{11} is not stationary upon the frame f^{10} , but is mounted upon a block f^{12} , arranged to slide back and forth in a slot of the frame f^{10} . The mechanism for thus reciprocating the roller f^{11} is preferably constructed and arranged as illustrated in detail in Figs. 8 and 9. It consists of a lever-arm h in slotted engagement at one end with the block f^{12} and pivoted at its other end to the frame f^{10} . Intermediate of its ends the lever-arm h is provided with a roller h' , bearing upon the periphery of a heart-shaped cam h^2 . The cam h^2 is secured to the shaft h^3 of a gear-wheel h^4 , the shaft h^3 having its bearings in the frame f^{10} . The teeth of the gear-wheel h^4 engage with a cam-rib h^5 , formed upon the periphery of one of the two disks comprising the faces of the reel e^{10} . As the frame f^{10} revolves about the reel e^{10} the gear-wheel h^4 and cam h^2 are rotated to cause the lever-arm h to reciprocate the block f^{12} and roller f^{11} . The cam h^2 being heart-shaped, as illustrated, will throw the lever-arm h and block f^{12} toward the left in Fig. 8, while in the opposite direction the pull of the wire will keep the roll h' in contact with the cam h^2 and effect the movement of the lever-arm h and block f^{12} toward the right in said figure. It follows that the wire e^{11} , passing over the roller f^{11} , is caused to reciprocate over the body of the reel e^{10} to be evenly laid thereon during the winding operation. The reel e^{10} has two disks or faces, one of which, e^{20} , is removable from the body e^{21} of the reel, and the other, e^{22} , is fixed to a hub or boss e^{24} and is radially slotted. The hub e^{24} is carried by a sleeve e^{23} , inclosed within the driving-sleeve b^3 , and is separated from an enlargement or collar b^5 on said sleeve b^3 by a washer e^{25} . The sleeve e^{23} is traversed by an arbor b^2 , which is provided with a nut b^6 , bearing against one member of a ball-bearing b^6 , the other member of said ball-bearing resting against the hub e^{24} to hold the hub e^{24} against the friction-washer e^{25} . A screw-nut b^7 serves to force the nut b^6 toward or away from the hub e^{24} .

The body e^{21} of the reel is formed of sections, preferably three in number, and normally surrounding the hub e^{24} . A clamping-screw e^{28} , passing through a radial slot of the disk e^{20} , serves to secure each section of the body to the front disk e^{20} . When loosened, the screws e^{28} permit the sections to collapse or decrease in diameter when the body e^{21} is removed from the hub e^{24} . Thumb-screws e^{27} serve to detachably secure the front disk e^{20} to the hub e^{24} . Each section of the body has at its back a pin e^{28} , swiveled to the section, and when projecting radially from the section adapted to enter one of the radial slots of the disk e^{22} , carried by the hub e^{24} . The pins e^{28} serve normally to confine the coil of wire on the body e^{21} and may be turned so as to traverse the body e^{21} diametrically after said body is removed from the hub e^{24} . This construction and arrangement of the reel e^{10} permits of the ready removal of the coil of wire e^{11} when a sufficient length of wire has been wound upon the reel. Thus upon unscrewing the thumb-screws e^{27} the front disk e^{20} , with the body e^{21} and coil of wire, can be drawn away from the hub e^{24} and back disk e^{22} . Upon turning the pins e^{28} and collapsing the sections of the body e^{21} the coil of wire can now be withdrawn from the body away from the front disk e^{20} . After withdrawal of the coil the reel e^{10} can be reassembled by a reverse operation of the parts. If the tension upon the wire e^{11} becomes too great during the winding operation, it is relieved by a slip of the hub e^{24} on the friction-washer e^{25} .

Having thus described the nature and objects of my invention, what I claim as new, and desire to secure by Letters Patent, is—

1. In a machine of the character described, a reel, a frame arranged to revolve around said reel, feed-rollers carried by the frame and having contiguous peripheries, said rollers arranged to revolve around the axis of revolution of the frame and to rotate in a plane passing through said axis, and means for positively rotating said rollers.

2. In a machine of the character described, a mechanism for unwinding or winding wire, comprising a reel, a friction device normally

holding said reel stationary, a frame revolving around said reel and guiding said wire, feed-rollers carried by the frame and arranged to rotate and feed the wire, and means for positively driving said rollers, said means controlled by the revolution of the frame.

3. In a machine of the character described, a mechanism for unwinding or winding wire, comprising a stationary reel, a frame revolving around said reel and guiding said wire, two arms projecting from said frame, a tubular bearing, in which the ends of said arms revolve, and through which bearing the wire passes, a cam-rib projecting from the face of said bearing, a gear-wheel carried by each arm and having teeth engaging the cam-rib, and a feed-roller carried by each gear-wheel, all arranged so that as the frame revolves the gear-wheels and rollers revolve and rotate to rotate and feed the wire.

4. In a machine of the character described, a mechanism for winding wire in coils, comprising a reel, a frame revolving around said reel, a roller carried by the frame and over which the wire is led, means for reciprocating said roller on said frame, and means controlled by the reel, whereby during the revolution of the frame around said reel the roller reciprocating means is operated.

5. In a machine of the character described, a mechanism for winding wire in coils, comprising a reel, a frame revolving around the reel, a block adapted to slide back and forth in said frame, a roller carried by said block and over which roller the wire is led, a lever-arm arranged to reciprocate the block and roller, a gear-wheel and cam arranged to operate the lever-arm, and a cam-rib carried by the reel and arranged to rotate said gear-wheel and cam.

In testimony whereof I have hereunto set my signature in the presence of two subscribing witnesses.

JOHN ALLEN HEANY.
